UNITED STATES PATENT OFFICE.

HENRY M. WALTMAN, OF LOMIRA, WISCONSIN.

RAILROAD-SPIKE.

SPECIFICATION forming part of Letters Patent No. 412,436, dated October 8, 1889.

Application filed June 17, 1889. Serial No. 314,663. (No model.)

To all whom it may concern:

Be it known that I, HENRY M. WALTMAN, a citizen of the United States, residing at Lomira, in the county of Dodge and State of Wisconsin, have invented certain new and useful Improvements in Railroad-Spikes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to railroad-spikes; and its objects are, first, to prolong the life of said articles; second, to increase the holding power of the spike; third, to protect the head from displacement while driving it in; fourth, to afford an alternative mode of holding the web of the rail—that is, either by the head or the shoulder of the spike—and, fifth, to secure these ends with structural simplicity and economy. I attain these aims by the device illustrated in the accompanying drawings, in which—

Figure 1 shows a cross-section of an ordinary rail, showing the method of its joinder to the tie as contemplated by my invention. Fig. 2 represents a side elevation of the spike, and Fig. 3 indicates a front elevation thereof.

The same designations indicate corresponding parts in the several views.

The ease of travel is greatly promoted by a well-ballasted road-bed and securely-laid rails. The present manner of fastening the rails by spikes as now constructed is defective, because in driving them the heads are

loosened by the reaction of the rails, and this is intensified by the jar occasioned by the passage of trains. Therefore I have devised a spike wherein the strain above mentioned shall be entirely borne by a shoulder, which prolongs, therefore, the integrity and service-ability of the spike.

The spike A has a pointed end *a* and a shoulder *b* at right angles both to the line of the spike A and of its head B.

C represents the rail, having a web *c*.

D is the tie.

It will be apparent that the spike A can optionally be driven so that its shoulder *b* shall abut the web *c*, or so that the head B will assume that position.

Having thus fully described my invention, what I claim is—

As an improved article of manufacture, a railroad - spike whose body A is uniformly straight centrally and tapers downwardly at one-fifth of the distance from the bottom to a point *a*, which is in the axial line of the body A, its upper terminus being provided with a shoulder *b* at right angles to the axis of the body A, surmounted by a head B, parallel therewith, and projecting on the side opposite said shoulder a greater distance beyond the body A than on the side adjacent thereto to secure a more stable joinder, as herein set forth and illustrated.

In testimony whereof I affix my signature in presence of two witnesses.

HENRY M. WALTMAN.
